UNITED STATES PATENT OFFICE.

HENRY C. TRIPP, OF AUBURN, NEW YORK.

DUPLEX CLEANER FOR WINDSHIELDS.

1,339,241.

Specification of Letters Patent. Patented May 4, 1920.

Application filed January 12, 1918. Serial No. 211,542.

To all whom it may concern:

Be it known that I, HENRY C. TRIPP, a citizen of the United States of America, and resident of Auburn, in the county of 5 Cayuga, in the State of New York, have invented new and useful Improvements in Duplex Cleaners for Windshields, of which the following, taken in connection with the accompanying drawings, is a full, clear, and 10 exact description.

This invention relates to certain improvements in duplex cleaner for wind shields involving the use of a pair of opposed wiping devices for simultaneously removing 15 dust, moisture, snow and other foreign matter from both sides of the transparent plates of said shield.

I am aware that certain forms of duplex cleaners for this purpose have heretofore 20 been proposed in which the wipers were mounted upon permanently connected spring arms necessitating the removal of the wipers from said arms in order to spring the latter over the guide-rail, along and 25 upon which the cleaner, as a whole, was mounted, but even under those conditions it became necessary to spring the arms apart to such an extent as to weaken the springs, so that when the device was installed for 30 use the contact of the wipers with the glass was more or less uncertain.

The main object of my present invention is to obviate the necessity for springing the wiper supports apart when installing or 35 removing the device upon and from its supporting rail, which object is accomplished by making one of the clamping devices detachable from the other device.

Another object is to provide for lateral 40 adjustments of the wipers relatively to the supporting arms to assure perfect contact between the wipers and opposite faces of the glass or shield.

A further object is to construct the wipers 45 so that they may be reversed when either wiping edge becomes worn or otherwise impaired.

A still further object is to provide simple means for moving the cleaner back and forth 50 across the glass plate of the shield.

Other objects and uses will be brought out in the following description.

In the drawings—

Figure 1 is an inner face view of an

ordinary double glass wind shield and my 55 improved cleaner mounted thereon.

Fig. 2 is an enlarged transverse sectional view taken on line 2—2, Fig. 1.

Fig. 3 is an enlarged detail sectional view of the clamping connection between the opposite cleaning devices taken in plane of 60 line 3—3, Fig. 2.

Figs. 4 and 5 are enlarged detail sectional views taken, respectively, in the planes of 65 lines 4—4 and 5—5, Fig. 2.

As illustrated, this cleaner is adapted to be used for simultaneously cleaning both sides of the transparent plate —a— of a wind shield —A— having the usual top and bottom rail —a'— and end rails —a''— and comprises a pair of opposed cleaning devices —1— and —1'— and a connecting member —2— constituting what may be termed a duplex cleaner which is movable across and in contact with opposite faces 75 of the glass from end to end thereof in a manner hereinafter described.

The opposed cleaning devices —1— and —1'— are substantially identical, in that each comprise a pair of similar interchangeable and reversible wipers —3— and supporting arms —4— and —4'— therefor, each wiper consisting of a pair of clamping plates —5— and an interposed flexible blade or scraper —6— of rubber or equivalent material.

The connecting member —2— for the cleaning devices preferably consists of a curved sheet metal plate having its inner concave face provided with a felt or equivalent lining —7— adapted to fit over and upon the upper face and opposite sides of the top rail —a'— of the wind shield frame to support the cleaning devices therefrom and permit them to be moved longitudinally 90 thereof without excessive noise or wear of the enamel of said rail, the length of the connecting member —2— being sufficient to properly hold the cleaning devices in opposed parallel relation during such movement and also when at rest.

The arms —4— and —4'— are also preferably made of sheet metal and are similar in form and size, except that one of them, as —4—, is shown as rigidly and permanently secured by brazing or equivalent fastening means at its upper end to one side of the head or connecting member —2—,

while the other member —4'— is detachably secured at its corresponding end to the other side of the head or connecting member —2—, and for this purpose is bifurcated or slotted at —8— for receiving a clamping bolt —9— on the head —2—, which clamping bolt is engaged by a thumb nut —10— for firmly clamping the adjacent end of the member —4'— in its operative position, and at the same time permitting it to be readily removed by simply loosening the nut —10— and withdrawing the arm 4' with the wiper thereon downwardly when installing or removing the cleaner as a whole upon and from the wind shield.

That is, when it is desired to install the cleaner upon the wind shield one of the cleaning devices, as —1'—, is removed in the manner described, whereupon the other cleaning device, as —1—, may be placed against the glass with the head —2— resting upon the top rail —a'— which assures contact of the inner edge of the corresponding blade —6— and holds said device in its proper position, after which the slotted end of the arm —4'— with the wiper 3 thereon is registered with the clamping bolt —9— and wedged between a pair of opposed flanges —11— on the adjacent side of the connecting member —2— by upward movement between the nut —10— and adjacent face of the connecting member —2— until the arm 4' reaches the limit of its upward movement as determined by the end of the slot engaging the bolt —9—, whereupon the nut —10— may be tightened by hand to firmly hold the detachable cleaning device in its adjusted position.

40 This detachability of one of the cleaning devices is important, in that it obviates the necessity for removing either of the wipers 3 from its supporting arm and also avoids excessive spreading of the arms —4— and —4'— in placing the cleaner, as a whole, over and upon its supporting rail, as —a'—, as would be necessary if both of the cleaning devices were permanently attached to the connecting member or head —2—.

45 The wipers —3— are preferably of the same length, nearly equal to the vertical width of the upper section of the sectional wind shield, or that portion of any other wind shield which affords clear vision ahead 55 of the machine, said wipers being preferably arranged in the same transverse plane and also in the same horizontal plane so as to engage directly opposite faces of the glass as the cleaner is moved back and forth 60 lengthwise thereof.

The clamping plates —5— of each pair preferably consist of flat sheet metal strips of the same width having straight and parallel longitudinal edges, and are provided at 65 intervals throughout their lengths with reg-

istering apertures for receiving clamping bolts or screws —12— passing through corresponding apertures in the blade —6— for firmly clamping the blades between the adjacent faces of said plates and together 70 with the plates constitute a holder for the blade —6—.

The opposite arms —4— and —4'— extend downwardly from the upper rail —a'— approximately half way across the upper 75 wind shield section —a— and are provided near their lower ends with opposite pairs of inturned flanges —13—, those of each pair being spaced apart a sufficient distance to receive between them the corresponding 80 wiper —3—, and are provided with registering laterally elongated slots —14— for receiving pivotal pins —15—, which are passed through registering apertures in said wiper to pivotally support the latter upon 85 the arms —1— and —1'— for lateral swinging movement and also for lateral adjustment to enable the inner edges of the blades —6— to be brought into contact with the adjacent faces of the glass —a— at all 90 points throughout their lengths.

That is, by pivoting the wipers to the lower ends of their supporting arms —4— and —4'— permits them to automatically contact at all points in their lengths with 95 the glass when properly adjusted, while the slots —14— permit the bodily adjustment of the wipers to compensate for wear and to assure a more perfect contact, the pivotal pins being held in their adjusted position by thumb nuts —16—.

The detachable cleaner section —1'— is preferably located at the inner side of the glass where it is readily accessible for removal or replacement by the driver from 105 the seat and is also provided with a handle —17— by which the cleaner as a whole may be moved back and forth when necessary.

Or, for greater convenience this movement 110 of the cleaner may be effected by means of a cable —18— having its ends attached to suitable eyes —19— on opposite sides of the detachable supporting arm —4'— and its intermediate portion passed around suitable sheaves —20— on the end rails —a'— so that the operator may engage any portion thereof for shifting the cleaner in either direction.

The wipers —3— are preferably reversible 120 so that either edge may be used next to the glass in case one edge becomes worn or otherwise impaired, and for this purpose, the blades —6— are caused to project slightly beyond opposite edges of their respective sets of clamping plates —5— and usually consist of flat pieces of rubber or equivalent flexible material capable of producing a wiping or brushing effect upon the surface of the glass without liability of 125 130

scratching or otherwise injuring the same as the cleaner is moved back and forth.

The connecting members —2— and the sections 4 and 4' are more or less resilient 5 and are tensioned so as to normally press the wipers against opposite faces of the glass, but if at any time the contact should not be sufficient to remove the foreign matter from the glass, the wipers may be readily set 10 up thereto by simply loosening the nuts —16— and moving the wipers inwardly; and then re-tightening the nuts to hold the wipers in their adjusted position without in any way interfering with the free piv- 15 otal movement thereof about the pivotal pins —15—.

The cleaner as a whole may be moved back and forth either by the handle —17— or cable —18—, and if it should become necessary to remove the cleaner at any time, this 20 can be done by simply loosening the thumb nut —10— and withdrawing the arm —4'— with the wiper —3— thereon downwardly to disconnect it from the head —2—, where- 25 upon the head and cleaner section —1— may

be readily displaced laterally by a slight upward and forward movement.

In reverse manner, the cleaner may be installed, thereby avoiding the necessity of removing either of the wipers from their supports and also avoiding excessive spreading of the arms 4 and 4', all of which features are important in the efficiency and convenience of operation of the device.

What I claim is:

The combination of a head slidable along and upon the top rail of a wind shield and provided at one side with a pendant arm and at its opposite side with a vertical guideway, a separate arm having its upper 40 end slidable in said guideway, means for detachably securing the last named arm in the guideway, and a pair of wipers pivotally mounted on the lower ends of said arms.

In witness whereof I have hereunto set 45 my hand this 28th day of December, 1917.

HENRY C. TRIPP.
